UNITED STATES PATENT OFFICE.

WILLIAM B. NOBLE, OF ROCHELLE, ILLINOIS.

PIANO-BENCH AND CABINET.

Specification of Letters Patent. Patented Dec. 21, 1915.

1,165,200.

Application filed September 21, 1914. Serial No. 862,786.

To all whom it may concern:

Be it known that I, WILLIAM B. NOBLE, a citizen of the United States, residing at Rochelle, in the county of Ogle and State of Illinois, have invented certain new and useful Improvements in Piano-Benches and Cabinets, of which the following is a specification.

The most satisfactory and comfortable bench for a person manually manipulating the keys of a piano is one having a flat top or seat disposed at a requisite height above the floor. The manipulation of a player piano, however, which is effected principally by the feet of the operator working the treadles requires a bench having a seat higher from the floor than the ordinary bench and also having the seat inclined forwardly so as to bring the feet of the operator in proper position on the pedals and also to prevent the operator from sliding away from the instrument.

The primary object of my invention is to provide a piano bench which can be used as an ordinary flat top bench when the piano is hand played and which can be converted into a player piano bench having an inclined seat disposed at a higher elevation than the horizontal seat, thus combining in one bench the requisite of an ordinary bench and player piano bench.

Another object of my invention is to provide a bench which can be converted from a flat seated bench into an inclined seated bench by a simple reversing movement of the top and which, when in either position, will afford a strong and substantial seat.

Another object is to provide a bench in which the top will be supported at all times during the reversing movements thereby obviating any danger of binding, twisting or breaking of parts, and rendering the reversing operations easy and simple.

A further object is to provide a piano bench which will also include a cabinet to hold music rolls, sheet music and the like, and so construct the cabinet and bench that the cabinet will be normally closed to exclude dust and dirt, but which is readily accessible from either side of the bench.

Another object is to so construct a bench of this character that it can be shipped in knocked down condition and readily assembled by the purchaser, thereby greatly reducing the shipping space required and correspondingly decreasing the cost of shippage.

To facilitate the explanation of my invention I have illustrated one preferred embodiment thereof on the accompanying sheet of drawings from which when considered in connection with the following description, the invention should be readily understood.

Referring to the drawings: Figure 1 is a perspective view of a bench embodying my invention. Fig. 2 is a longitudinal sectional view of the bench taken on the line 2-2 of Fig. 4. Fig. 3 is a horizontal sectional view taken substantially on the line 3-3 of Fig. 4. Fig. 4 is a transverse sectional view on the line 4-4 of Fig. 2; Figs. 5, 6, and 7 are views similar to Fig. 4 showing the bench top in different positions; and Fig. 8 is an enlarged plan sectional view taken on the line 8-8 of Fig. 4.

On the drawings reference characters 8 and 9 designate the end pieces or uprights of the bench. These pieces, of course, may be of any preferred ornamental design and may be made of any desired length and width. The end pieces are connected together by side pieces 11 and 12, preferably fastened by screws 13, so that the parts may be assembled, the end pieces being recessed on their vertical edges to receive their side pieces so that the outer faces of the sides will lie flush with the edges of the ends as shown in Fig. 1. The end pieces 8 and 9 are provided on their inner faces some distance from the lower ends thereof with cleats 14 and 15, respectively, and the sides 11 and 12 are provided with similar cleats 16 and 17, respectively, disposed in alinement with the end cleats 14 and 15. These cleats are adapted to support the bottom 18 of the cabinet, suitable screws 19, preferably four in number, being employed to hold the bottom in place. The cleats 21 and 22 are also mounted on the inner faces of the ends 8 and 9, respectively, substantially in alinement with the upper edges of the sides 11 and 12, and the tops of the cleats 21 and 22 are faced with strips of felt 23 or other suitable material which will permit the cabinet top or seat 24 to slide thereover without marring or scratching the same.

It will be manifest that the construction thus far described provides a cabinet or compartment adapted to receive music rolls, sheet music or other articles which it will be desirable to keep in convenient relation to a piano.

Each of the end pieces is provided above

the cabinet on its inner face with a groove 25 adapted to receive a stud or pintle 26 projecting longitudinally from the center of the seat board 24, as best shown in Fig. 8. 5 The pintle being preferably equipped with a base 27, secured to the end of the seat board by screws 28. Each pintle, as shown in Fig. 8, is provided at its end with a head, and a slotted strip of metal 29 or a plurality of strips spaced apart are secured to the ends by screws or other fastening means so as to overlie the edges of the groove 25 and prevent withdrawal of the pintle from the groove 25. This construction provides a 15 guideway in which the seat board may be moved up and down vertically and rotated or reversed on its pintle.

The ends of the seat board are provided with strips of felt 30, Fig. 8, or other suitable material, so that the ends of the board will not scratch or mar the inner sides of the uprights when the seat board is being reversed. When the bench is so constructed, the upper ends of the groove 25 are open 20 to permit the introduction of the pintles 26 therein, and if the bench is assembled, the upper ends of the groove are closed by top pieces 31 and 32 which prevent the pintles from being lifted out of the grooves. The 25 top pieces 31 and 32 are secured in position by a plurality of wood screws 33.

In order to provide an inclined seat of the required height to be used as a bench with player pianos, I have secured upon one 30 face of the seat board 24 an auxiliary seat board 34 carried by a frame 35, shaped to give the required inclination to the board 34 on the main seat. Board 24 is in horizontal position as shown in Figs. 1 and 4. 35 The inclined seat board 34 is shown as only partially as long as the main seat board for the reason that only one person sits on the bench when operating a player piano, while two may occupy the bench to play a piano. 40 Obviously, however, the length of the auxiliary seat board may be increased or diminished if desired.

When the seat is positioned, as shown in Figs. 1, 2, and 4 the bench is adapted to be 45 used as a player piano bench and the seat board 24 also serves as a cover for the cabinet beneath. If it should be desirable to use the bench in connection with a manually manipulated piano a horizontal seat of the required height is obtained by simply reversing the seat board on its pintles. This reversal is effected by lifting the seat board in its grooves first to the position shown in Fig. 5 to permit the lower edge thereof to 50 swing inwardly on the cleats 21 and 22. The seat is then reversed through the position shown in Fig. 6 to that shown in Fig. 7. During the reversal of the seat board it is supported at its lower edge by the felt 55 covered cleats 21 and 22 so that there is no

danger of the seat dropping suddenly, and the reversing movement is accomplished quietly and easily. The felt covering of the cleats prevents marring and scratching the lower edge of the seat board during the reversing movements. Obviously the seat is capable of being reversed in either direction and when in operative position completely covers the cabinet underneath. Access to the cabinet may be obtained from either side 70 of the bench by simply lifting one edge of the reversible seat.

My improved bench as above described is simple in construction and cheap to manufacture, and it will be obvious that it comprises but eight pieces which may be knocked down and packed into a relatively small space for shipment. The pieces shipped comprise the ends 8 and 9, the sides 11 and 12, the bottom 18, the seat 24 carrying the auxiliary seat 34 and the top pieces 31 and 32. In assembling the bench the sides 11 and 12 are first attached to the ends, the bottom 18 is secured in position, the seat board pintles 26 are introduced into the upper ends of the grooves 25 and finally the top pieces 31 and 32 are fastened into position.

It is believed that my invention will be fully understood from the foregoing without further description and it should be obvious that various modifications in the structural details disclosed may be resorted to without exceeding the scope of the invention.

I claim:

1. A piano bench and cabinet comprising, a pair of end members each provided with a transversely extending way on one face thereof and with a slot extending from adjacent said way to the top of the end member, a pair of side members adapted to connect said end members together to form a rectangular casing, a bottom for the casing, a seat board adapted to serve as a top to the casing, and being provided with a raised seat on one face thereof and at each end with an extension adapted to locate in and be guided by a slot in one of the end members, and an arm-rest adapted to be attached to the top of each end member and to cover the open end of the slot therein.

2. In a piano bench, the combination of upright end members, a seat board disposed intermediate the same below the top thereof and provided on one face with a raised seat, each end member being provided intermediate its top and the seat board with a vertically disposed guideway, and a pintle secured to each end of the seat board and located in the adjacent guideway, said pintles being movable in said guideway to permit vertical and rotative movement of said seat board so as to position either of its faces uppermost.

3. In a piano bench, the combination of upright end members each provided at its inner side with a horizontal guideway and a vertical guideway extended above the horizontal guideway, a seat board interposed between said end members, adapted to rest upon and be guided by said horizontal guideways and provided with a raised seat on one face, and means coöperating with the ends of the seat board and said guideways to maintain the seat board in central relation to the piano bench and permitting the seat board to be raised from either side and turned on said means through an arcuate path to a reversed position, the lower edge of the seat board resting upon and being guided by said horizontal ways during said reversing movement.

4. A piano bench and cabinet, comprising a pair of upright end members, a pair of side members connecting the end members and forming therewith a rectangular casing,

the end members being extended above said side members and provided on their inner faces with vertically disposed slots and horizontal guideways substantially flush with the upper edges of said side members, a seat board forming a top for the casing and provided on one face with a raised seat, and pintles projecting from the ends of the seat board into the adjacent slots in the end members forming a movable pivotal connection between said end members and the seat board which permits either side of the seat board to be raised and swung in an arcuate path to the opposite side of the cabinet, the seat board during such movement turning on its pintles and resting on and being guided by the horizontal ways.

WILLIAM B. NOBLE.
